UNITED STATES PATENT OFFICE

CLARENCE P. WOOD, OF NEW YORK, N. Y., ASSIGNOR, BY MESNE ASSIGNMENTS, TO
ROBERT B. KILLGORE, OF SHORT HILLS, NEW JERSEY

TURNTABLE DRIVE

Application filed December 28, 1929. Serial No. 417,075.

My invention relates especially to the phonographs or record revolving mechanism used in talking moving picture apparatus.

It has generally been the practice to drive 5 the phonograph end of such apparatus by means of a separate motor and then use mechanism to synchronize the phonograph and projector. This was found to be necessary by reason of the fact that when the phonograph and projector were mechanically connected and driven by a single motor any 10 irregularity in the feed of the projector was transmitted to the phonograph and caused the turntable to almost imperceptibly accelerate or retard resulting in a wavering reproduction of the sound groove in the record.

It is my object to overcome this defect in direct coupled machines by means of the phonograph hereinafter described, as well 20 as to provide a simple, cheap and sturdy phonograph which can be quickly and easily connected to any projector head and which does not interfere with the door in the projector through which access is had to the mechanism 25 inside the head for oiling and cleaning purposes.

In the drawings Fig. 1 is a cross-sectional view of my improved phonograph; Fig. 2 a view of the structure of Fig. 1 on the line 30 2-2 thereof; and Fig. 3 a detail view of the mechanical filter on the turntable shaft.

My phonograph comprises a base 1, carrying a vertically adjustable housing 2, held at any required height by a set screw 3. 35 This housing carries a divided turntable shaft 4-4' whose meeting ends are preferably rounded as shown in Fig. 1. The upper section 4 terminates in the record centering pin 5. The lower section 4' of the shaft rests in the bearing 6 and against the thrust bearing 7. The upper section 4 of the shaft rests in the bearing 8 and is provided with a thrust bearing 9.

The two sections of the shaft are coupled 45 together by a resilient, elastic mechanical filter comprising a yoke 10 on the shaft section 4' and a like yoke 11 on the shaft section 4, with an elastic rubber disk 12 secured to the yoke ends, which are in staggered relation 50 as shown in Fig. 3.

The turntable 13 is very heavy, about 120 pounds in practice, so that the inertia while revolving will resist the effects of any slight variations in the speed of the driving mechanism and hold the turntable to an absolutely steady speed. 55

The turntable and its shaft are revolved by means of a worm and gear. A gear 14 is mounted on the shaft section 4 below the mechanical filter and a worm 15 is cut on the shaft 16 which is carried in the bearings 17 and 18 and projects through the bearing 18, the extended end carrying a pin 19, the bearing 17 receiving the drive thrust. 60

The coupling shaft connecting the phonograph to the projecting head is made in sections. The first section is in the form of a sleeve 20 having a notch 21 in its end adapted to engage the pin 19 and carries a disk 22 on its other end. The second section is in 70 the form of a sleeve 23 provided with slots 24 and carries a disk 25. The disks 22 and 25 are coupled by means of a flexible rubber disk 26 to form a cushioned universal joint. The third section is in the form of a shaft 75 27 which slides in the sleeve 23 and carries a pin 28 engaging the slot 24, the free end carrying a disk 29. A spring 30 wound around the shaft 27 forces the shaft 27 and sleeve 23 apart. The fourth section comprises a shaft 30 with a pin 31 at one end and a disk 32 at the other. A flexible rubber disk 33 connects the two disks 29 and 32 to form a cushioned universal joint. A notched nut 80 or coupling piece 34 is adapted to be secured to the exposed end of the main or crank shaft of the projecting head and engages the pin 31.

An arm 35 may be mounted on the housing 2 to carry the reproducing or pick-up 90 head of the phonograph. 85

In operation the phonograph and projecting head are coupled up to operate as a unit, being driven by the motor of the projecting machine. The record and film each has the starting point marked thereon and after the appropriate adjustments are made the motor is started and the projecting machine feeds the film and drives the phonograph in 95 synchronism therewith. 100

- The unavoidable slight irregularities in the speed of the projecting head are absorbed in the flexible rubber disks 12, 26 and 33 before they can overcome the inertia of the 5 very heavy turntable 13 so that any slight variations in the speed of the projecting head will cause the rubber disks to deform slightly to filter or absorb the irregularities without affecting the constant speed of the turntable.
- 10 Should the projecting head be suddenly stopped the gear 14 will climb the worm 15 slightly lifting the mass of the turntable and then the weight of the turntable will 15 cause it to slowly settle back, coming to a shockless stop.
- 15 When the door of the projecting machine has to be opened to oil the interior mechanism the shaft 27 is slid further into the sleeve 23 20 by compressing the spring 30 and the pins 31 and 19 cleared from the slots so that the projecting head is in the same condition that it would be were there no phonograph associated therewith.
- 25 The principle involved may be summed up as the utilization of the mass of a very heavy turntable to store up inertia to prevent speed variations and the interposition of mechanical filters between the turntable and the projecting machine to absorb any irregularities 30 in the drive.

I claim:—

- A phonograph comprising a housing, a divided turntable shaft therein, a heavy turntable on the upper section of said shaft, a yoke on the lower end of the upper shaft section, a second yoke on the upper end of the lower shaft section, an elastic connection engaging both of said yokes, a worm gear on 40 the lower shaft section, a driving worm engaging said worm gear and adapted to be connected to the main shaft of a moving picture projector, whereby on the sudden stoppage of said turntable the rotary movement 45 thereof is converted into a vertical movement for stopping said turntable without shock or jar.

In testimony whereof I have hereunto subscribed my name.

50 CLARENCE P. WOOD.
